F. H. Smith.

United States Patent Office.

FRANCIS H. SMITH, OF BALTIMORE, MARYLAND.

Letters Patent No. 80,231, dated July 21, 1868.

IMPROVED BRICK-MACHINE.

The Schedule referred to in these Letters Patent and making part of the same.

TO ALL WHOM IT MAY CONCERN:

Be it known that I, FRANCIS H. SMITH, of the city and county of Baltimore, and State of Maryland, have invented a new and improved Machine for Moulding Bricks; and I do hereby declare the following to be a full, clear, and exact description thereof, reference being made to the accompanying drawings, making a part thereof, and as these improvements are in fact made upon the machine for which Letters Patent were granted me on the 3d October, 1854, No. 11,752, I refer also to the drawings thereof, and now make the same a part of this application, in order more clearly to set forth my improvements, and enable others skilled in the art to make and use the same.

All that now remains of the former machine are the bed-plate, fig. 4, the hub and wooden step, fig. 5, the screw, fig. 6, with the main shaft thereto attached. All the rest is new.

Of the present invention—

Figure 1 is an isometrical or external view, showing the brick-moulding machine in working operation.

Figure 2 is a side view of the same.

Figure 3 is a horizontal section, showing all parts of the machine below the section-line *y y* marked in fig. 2.

Figure 4 is a top view, showing the gearing.

Figure 5 is a profile, showing the spindle and interior of the pug-mill.

Figure 6 is a detached view of one of the tri-armed cutters or blades.

A represents the principal frame of the machine.

B, the sides of the octagon or eight-sided tub called the pug-mill. Four of the sides are of iron, that the three fixed knives *b* may be cast thereon. They are so placed that the tri-armed blades *a* may pass between them, by which the large lumps of clay are broken up, and become properly comminuted and tempered. If the shaft had the usual blades in sets of four, then all of them would bear upon the fixed knives *b* at the same time, but by having them in sets of three, only one set presses against the knives *b* at the same instant, requiring much less power to operate.

The shaft C is provided with tri-armed curved blades, fig. 6, and on the lower part of said shaft is secured a spiral flange, H, to serve as a pressure, and force the tempered clay through openings or gratings *c* in the bed-plate; the number of said openings corresponding with the number of moulds in one frame, according to the size or capacity of the machine, that is to say, for one mould, four moulds, or six.

The mould of the former patent did not answer the expectations formed of it, and very soon had to be abandoned.

The present one, Figure 8, given in three views, a plan, a longitudinal section, and a transverse section, is an open portable mould, precisely like those in common use, having one, four, or six in one frame.

The peculiarity consists in the plate or mould-carrier O, on which it rests while passing on the ways beneath the bed-plate Z. It is provided with four lugs or ears *d*, to steady and keep it in its proper place.

It is important that the mould be placed precisely in its proper position beneath the openings *c* in the bed-plate Z, for the variance, of half an inch, or even less, would be fatal; for, unless the dividings of the mould be placed precisely beneath and corresponding dividings in the bed-plate, the clay, in its passage through, would wipe off the sand from the mould with which it was dusted, and the brick would not slip. No provision was made for this in the former invention, but is now effected in the following manner:

The mould, fig. 8, and its plate O, are moved on the ways by the bar N, which is connected, by the links M, with the lever I. The upper end of said lever is connected, by the wooden arm J, with the crank-wheels f, at the ends of the shaft K, which receives its motion from the shaft E, through the medium of spur-gear P.

The shaft E receives its motion from the shaft G, through the medium of spur-gear F. On the end of this shaft G is the driving-pulley R.

On top of the spindle C is the bevel-wheel D, which receives its motion from a bevel-pinion on the shaft E. The fling of the levers I and consequent motion of the bar N are governed by the distance of the crank-pin

g from the centre of the crank-wheel *f*, and any slight difference may be regulated by set-screws *q*, passing through slots, which connect the links *M* with the lower ends of levers *I*.

The arm *J* is made of wood, in order that it may break in case of obstruction, and thus act as a safety-guard to the machine.

An empty mould is placed in position under the bed-plate at each revolution, and remains at rest while being filled. The bar *N* then recedes to receive another mould, which pushes along the one just filled, and an empty one takes its place. Thus, the train of moulds is kept in motion, and, as they appear in front, are borne off to the drying-floor, and the plates passed back to receive other moulds.

In the former machine, the clay was sliced off by the broad knife, Figure 9, hung on pivots, but the loss of time in keeping this clean compelled it to be laid aside. I now do this better by bringing the mould and bed-plate so close to each other, that the mould comes out completely shaven; but this must be regulated, even to the sixteenth of an inch. I do this by the set-screws *e* at the corners of the bed-plate.

Having thus fully described the nature of my invention, what I claim as new, and desire to secure by Letters Patent, is—

The adjustable bed-plate *Z*, when vertically adjusted by means of the set-screws *e*, the mould-carrier *O*, provided with its open mould and lugs *d*, and the jointed lever-arms *M I*, and wooden arms *J*, all arranged together and operated as and for the purpose herein set forth.

The above specification of my invention signed by me, this 18th day of March, 1868.

F. H. SMITH.
